(57) **CLAIM**

We claim the ornamental design for a computing device display, as shown and described.

DESCRIPTION

FIG. 1 is a rear perspective view of a computing device display showing our new design;

FIG. 2 is a front perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The dash-dash broken lines in FIGS. 1-7 illustrate portions of the display that form no part of the claimed design. The short dash-long dash broken lines in FIGS. 1-7 illustrate boundary lines which form no part of the claimed design.
